HOUSING FOR A CARTRIDGE TAPE PLAYER OR SIMILAR ARTICLE

Jack Prygoff, Queens County, N.Y.
(167-05 12th Ave., Whitestone 57, N.Y.)

Filed July 12, 1963, Ser. No. 75,776

Term of patent 3½ years

(Cl. D26-14)

FIG. 1

FIG. 2

FIG. 1 is a front, top and left side perspective view of a housing for a cartridge tape player or similar article, showing my new design; and

FIG. 2 is a right side elevational view thereof, to an enlarged scale.

The back surfaces of the housing, not shown, are conventionally functional unornamented surfaces. The grille-work fragmentarily shown is continuous within the areas indicated.

I claim:

The ornamental design for a housing for a cartridge tape player or similar article as shown and described.
